UNITED STATES PATENT OFFICE

2,541,223

VIBRATOR

Harold V. Elliott and Brooks H. Short, Anderson,
Ind., assignors to General Motors Corporation,
Detroit, Mich., a corporation of Delaware

Application May 15, 1948, Serial No. 27,237

1 Claim. (Cl. 200—90)

1

The invention relates to apparatus for converting direct current from low voltage to higher voltage and more particularly the vibrator which distributes current in succession to the primary windings of a transformer.

An object of the invention is to provide a vibrator which can be easily adjusted to obtain the required separation of its contacts. This is accomplished by the provision of contact blade supports or stops each having a body portion attached to the frame and extending laterally beyond the adjacent side edge of the vibrator frame, a head portion engaging a blade at the end thereof carrying a contact and extending laterally beyond the adjacent side edges of the frame and blade and a neck portion narrower than the body portion and the head portion and located wholly beyond the adjacent side edges of the frame and blade and adapted to be bent by the application thereto of a rod having in one end thereof a notch receiving the neck portion and by the turning of the rod while thus engaging the neck portion in order to adjust the contact on the blade relative to the adjacent blade supported contact.

Further objects and advantages of the present invention will be apparent from the following description, reference being had to the accompanying drawings, wherein a preferred embodiment of the present invention is clearly shown.

In the drawings:

Fig. 1 is an enlarged scale longitudinal sectional view of the vibrator, and its container.

Fig. 2 is a view of the vibrator in the direction of arrow 2 of Fig. 1.

Fig. 3 is a view of the vibrator magnet spool looking in the direction of arrow 3 of Fig. 1.

Fig. 4 is a sectional view on line 4—4 of Fig. 3.

Fig. 5 is a reduced scale view of the tool which is used in adjusting the vibrator contacts.

Fig. 6 is a wiring diagram showing the connections of the vibrator with a current source and primary windings of a transformer.

Fig. 7 is a side view of the vibrator frame.

Fig. 8 is a side view of the vibrator reed assembled with an armature and contacts.

Fig. 9 is a view of an assembly of a spring blade and one of the vibrator contacts.

Fig. 10 is a view in the direction of arrow 10 of Fig. 9.

Fig. 11 is an enlarged scale view partly in longitudinal section of one of the contacts welded to a contact rivet.

Referring to Figs. 1 and 2 the vibrator com-

cuit including a core 21 and pole pieces 22. The core 21 extends through a spool which comprises parts 23 and 24 of molded insulating material upon which are wound a tape layer 25a, a coil 25 of wire and a tape layer 25b. An insulating spacer 26 and the assembly of spool and coil are placed upon the core 21 while the pole pieces 22 are located as shown in Fig. 7. After making this assembly the parts 22 are bent on lines 22a into parallelism as shown in Fig. 2. One end of the coil 25 marked 27 in Fig. 1 is attached to the frame 20 and the other end is connected to a lead wire 28. The corners of core 21 are deformed to retain the spool.

15 Screws 30 secure to the frame 20 a stack of parts comprising an insulator 31, metal contact springs 321 and 331 in the same plane carrying respectively contacts 341 and 351, metal contact spring supports 361 in the same plane, an insulator 31, a metal spacer plate 38, a terminal plate 39, a reed 40, a second terminal plate 39, a second spacer plate 38, a second insulator 31, metal contact spring supports 361 in the same plane, metal contact springs 32r and 33r in the same plane and supporting, respectively, contacts 34r and 35r, an insulator 31, a metal plate 41. All parts of said stack parts are insulated from the screws 30 by nonconducting sleeves 42 except the plate 41. Lock washers confined between the heads of the screws 30 and the plate 41 resist accidental loosening of the screws. The four insulators 31, the two spacers 38, the plate 41, the two terminals 39 and the reed 40 each have two holes receiving the bushings 42. The contact springs and the contact spring supports each have one hole for receiving a bushing. Supports 36 each have a notch 37 for receiving a tang 37a of the contact spring. The grain of the metal of the reed is in the direction of the longer dimension of the reed.

40 The contacts 341, 351, 34r, 35r engageable respectively with movable contacts 541, 551, 54r, 55r each having a spherical face as shown in Fig. 11 and welded to a rivet 50. Rivets carrying contacts 541 and 551 are attached to a resilient contact support 571 and the rivets carrying contacts 54r and 55r are attached to resilient contact support 57r. Supports 571 and 57r are attached by rivets 58 to the reed 40. An armature 60 is attached to the reed 40 by rivets 61 passing through the armature, the reed and a plate 62 against which the rivets are upset.

45 A wire 70 connects frame 20 with terminal plates 39 and reed 40 and plates 39 are connected by wire 71 with terminal 72. Wire 28

50 Referring to Figs. 1 and 2 the vibrator com-

55 prises a frame 20 which provides a magnetic cir-

(Figs. 2 and 6) is connected with blade 33r which carries contact 35r and this blade is connected by wire 73 with a terminal 74. The blade 32r which carries contact 34r is connected by wire 75 with terminal 76. The blade 32l which carries contact 34l is connected by wire 77 (Figs. 1 and 6) with a terminal 78. The blade 33l which carries contact 35l is connected by wire 79 (Fig. 6) with a terminal 80.

The five terminals 72, 74, 76, 78 and 80 three of which are shown in Fig. 1 are supported by a nonconducting disc 81 that provides a cover for a case 82 enclosing the vibrator and sponge rubber members 83, 84, 85 and 86 which provide a cushioning support for the vibrator and its connections with the terminals.

The vibrator is connected as shown in Fig. 6 with the current source and primary windings of a transformer. Terminal 72 is connected by wire 80 and switch 91 with a storage battery 82 having one terminal grounded. The terminals 74, 76, 78 and 80 are connected respectively with transformer primary sections 84, 86, 88 and 100 which are grounded at 101. The transformer secondary 102 is connected with a rectifier, the output terminal of which is connected with the apparatus, such as a high frequency ignition system, requiring for its operation relatively high voltage direct current. Satisfactory operation of the vibrator is obtained provided the contact closing periods of all of the vibrator contacts are such that energization of the four sections of the primary of the transformer are equalized. In order to determine whether such equalization exists the vibrator is tested by the apparatus disclosed in copending divisional application, Serial No. 109,198, filed July 18, 1949 and its relatively fixed contacts are adjusted during the test in order to obtain equalization. Equalization is obtained by adjusting the contact blade supports 36 until wave forms shown on an oscilloscope screen are equalized.

If the wave forms on the oscilloscope screen are not equal, an adjustment of the fixed contacts is made by bending the contact spring supporting plates 36 against which the contact supporting springs are biased. It will be observed that each plate 36 has a relatively narrow neck 36n, the bending of which will displace the head 36h of the plate 36 so as to change the normal contact gap. The bending of the neck 36n is effected by the T-shaped tool 220 shown in Fig. 5 which includes a handle integral with a shank 221 having a notch 222 wide enough to easily receive the neck 36n. By turning the handle the plate 36 can be easily bent in order to change the location of the fixed contact of a pair relative to the movable contact.

While the embodiment of the present invention as herein disclosed, constitutes a preferred form, it is to be understood that other forms might be adopted, all coming within the scope of the claim which follows.

What is claimed is as follows:

A vibrator for use in a low-to-high voltage D. C. converter comprising a magnetizable frame providing a core having a face at right angles to its axis, a magnet coil on the core, a magnetizable armature, a reed supported by the frame and normally supporting the armature in a position offset from the core and for movement of said armature closer to the core face when the magnet coil is energized, side contacts supported by the reed, resilient blades supported by the frame, contacts respectively attached to the blades and engageable respectively with the reed supported contacts, and metal blade supports located between the reed and the blades and against which the blades are respectively biased, each support having a body portion attached to the frame and extending laterally beyond the adjacent side edge of the frame, a head portion engaging a blade at the end portion thereof carrying a contact and extending laterally beyond the adjacent side edge of the frame and blade and a neck portion substantially narrower than the body portion and the head portion and located wholly beyond the adjacent side edges of the frame and blade and adapted to be bent by the application thereto of a rod having in one end thereof a notch receiving the neck portion and by the turning of the rod while thus engaging the neck portion in order to adjust the contact on the blade relative to the adjacent reed supported contact.

HAROLD V. ELLIOTT:
BROOKS H. SHORT.
